UNITED STATES PATENT OFFICE.

MATILDA MAY KERR, OF HUTCHINSON, KANSAS.

DESIGN FOR A CURTAIN-FIXTURE.

42,689.

Specification for Design.

Patented July 2, 1912.

Application filed April 3, 1912. Serial No. 688,310. Term of patent 7 years.

To all whom it may concern:

Be it known that I, MATILDA M. KERR, a citizen of the United States, residing at Hutchinson, in the county of Reno and State of Kansas, have invented a new, original, and ornamental Design for Curtain-Fixtures, of which the following is a specification, reference being had to the accompanying drawing, forming part thereof.

In the drawing, Figure 1 is a side elevation of a curtain fixture, showing my design, and Fig. 2 is a front elevation of the same.

I claim:

The ornamental design for a curtain fixture, as shown.
